UNITED STATES PATENT OFFICE.

JOHN H. DORMAN, OF NEW YORK, N. Y.

TAPPING AND DRILLING TOOL.

943,009.

Specification of Letters Patent. Patented Dec. 14, 1909.

Application filed August 1, 1908. Serial No. 446,426.

To all whom it may concern:

Be it known that I, JOHN H. DORMAN, a citizen of the United States of America, residing at New York city, in the county of New York and State of New York, have invented certain new and useful Improvements in Tapping and Drilling Tools, of which the following is a specification, reference being had therein to the accompanying drawing.

This invention relates to those attachments for tapping tools or chucks adapted to be applied to the rotating chuck of a drill press for the purpose of providing means which will yield and refuse to drive the tap whenever the latter reaches bottom or whenever torsional strain on the tap becomes too great; and my device also relates to superior means for reversing the rotation of the tap in the act of backing it out of the work.

The object of my invention is to provide a tool of this kind which will run smoother, last longer, and be lighter to handle and more easy to take apart and put together whenever repairs or inspection are necessary.

To these ends my invention consists in the peculiar features and combinations of parts more fully described hereinafter and pointed out in the claims.

In the accompanying drawings, Figure 1 represents a side elevation of my complete device, the casing and some of the other parts being shown in section, and the clutch being shown coupled as in tapping adjustment. Figs. 2 and 3 are horizontal sections through the lines $\alpha\alpha$ and $\gamma\gamma$, respectively, of Fig. 1. Fig. 4 is an external view of my complete device as when used on an ordinary drill press. Fig. 5 is a vertical section through my complete invention.

Fig. 6 is a transverse section through the chuck or tool holder. Fig. 7 is a sectional view of the upper end of the chuck spindle showing the mode of attaching the clutch-bar. Figs. 8 and 9 are top and sectional views respectively of the clutch-bar detached, and Fig. 10, a top view of a detail showing the upper ends of the two pinion spindles and the manner in which they are locked against rotation.

The friction driving devices and the reversing gears are inclosed within a casing 1, made of aluminum for the sake of lightness, which is a great desideratum in a tool of this character, and I have therefore made all the parts with a view to getting them as

light as consistent with strength and durability.

2 represents a tapering shank having the usual squared end and adapted to be locked in the chuck 3 and driven by a continuously rotating vertical shaft 4 in the end of the overhanging arm 5 of an ordinary drill-press 6, my device being raised and lowered over a table 7, all of which elements are too well known to need further description.

The gearing is retained within the aluminum casing by a removable base-plate or cover 9 fastened by long screws 10 which enter external longitudinal lugs 11 and provide a strong joint. This cover 9 is made of cast iron in order to receive the bearings for the moving parts centered in it and mounted on it, and it is provided with a circular embossment 9^a cut on a center coincident with that of the chuck-spindle, and so as to leave in the edge of the cover a circular recess 9^b which permits the embossment to fit exactly the interior of the casing, the two being turned from the same center whereby perfect alinement of the parts is assured.

Within the housing, composed of the casing 1 and the removable cover 9, are located three clutch devices, first, a friction clutch adapted to give up under excessive strain, thereby preventing the breakage of slender drills and taps; second, a positive clutch for driving a tap into the work, and third, a positive clutch for backing the tap out of the work, all of which arrangement is common to the art.

My peculiar friction clutch will first be described. It consists of a circular disk 12 formed integral with a hollow elongated vertical shaft 13 which extends up through the longitudinal center of the device, terminating flush with the top of the casing 1, where it is connected by a screw 14 to the driving shank 2. This shaft 13 is surrounded by a friction sleeve or bushing 15 having an integral circular flange 16 at its lower end adapted to engage a corresponding shoulder 17 formed on the inside of the casing. This bushing 15 is preferably made of phosphor bronze to withstand the wear of the revolving hollow shaft 13. The shank 2 is provided with a circular, horizontal collar 18 which overlaps and bears upon the end of the friction sleeve 15 for the purpose of preventing the screw 14 of the shank 2 from unscrewing prematurely.

When the shaft 4 of the continuously driven drill-press is set in motion, it also drives the shank 2 continuously, and in one direction, which shank in turn drives the 5 hollow shaft 13, and the latter drives the drill or tap which operates upon any suitable piece of metal work held upon the table of the drill press. The intermediate mechanism by which the chuck is driven consists 10 of a comparatively large, horizontal gear 19 clutched to turn with the hollow drive shaft 13 by means of a circular nut 20 surrounding the lower portion of said shaft at a point a short distance above the friction 15 disk 12. This nut 20 has a left-hand screw thread to engage that on the shaft, and when screwed down clamps a central web 21 of the gear 19 so that the two will revolve together. Washers 22 and 23 of vulcanized 20 fiber or other suitable material are interposed between the parts to take up wear and to increase friction. A set screw 25 is employed to lock the nut 20 at any desired point of adjustment. The nut may be adjusted from the outside of the casing by inserting a tool 26, shown in dotted lines, through a recess or hole 27 in the casing into the radial hole 24, thereby locking the two parts together. When the nut and casing 30 are thus locked together, the casing should be turned bodily while the shank 3 is held against turning, whereby the nut will tighten or loosen to increase or diminish the driving friction between the drive shaft 13 35 and the gear 19. The revolution of gear 19, when the clutch is in, actuates a reversing gear 28 through the medium of three intermediate smaller gears 30, 31 and 32, centered to revolve on two vertical fixed shafts 40 33 and 34 in an offset 35 of the casing 1. From the adjacent faces of these two larger 45 gears 19 and 28 project four short cylindrically shaped clutching lugs 38 and 39, two on each gear. These clutch lugs are 50 adapted to be alternately engaged, for driving or reversing the tap, by a transverse clutch-bar 36 which passes loosely through the chuck-spindle 29 around which said larger gears 19 and 28 revolve. The chuck-spindle 29 has an endwise movement in its 55 housing, the play of which is limited by the clutch-bar 36 coming in contact respectively with the upper and lower gears 19 and 28. This bar also prevents the spindle from dropping out.

The chuck-spindle 29 drops down into extended position by its own gravity. When the whole tool is lowered and the tap comes in contact with the work below, said spindle 60 is pushed up into the housing until the clutch-bar 36 engages the sides of the lugs 38 on the upper gear 19 and the bar and gear will revolve together to operate the tap. As this clutch-bar 36 is slightly loose 65 in the spindle, its opposite arms will accom-

modate themselves with equal pressure on both lugs 38 to drive the spindle. The underside of the clutch-bar is recessed longitudinally to retain the bar, as shown in dotted lines in Fig. 7. The clutch-bar also 70 has slight endwise play. The additional means for accomplishing this triple movement of the clutch-bar consist of a round locking and pivoting pin 39, rounded at both ends, and contained within a longitudinal bore 40 intersecting the transverse slot 41 in the spindle and extending therefrom to the upper end of the spindle. The bore is considerably larger than the diameter of the round pin in order to allow the lower end 75 of the pin to move laterally with slight longitudinal movements of the clutch-bar 36. The clutch-bar is loosely and pivotally held at the middle by this pin, and cannot get out of its slot because of the shoulders 42 80 which come in contact with the lower edges of the clutch-bar recess 41. A shallow recess 43 is cut into the spindle at the upper and lower edges of the recess 41 to give the shoulders on the clutch-bar a better bearing 85 surface. The round clutch-bar locking pin is held within the central bore 40 by a longitudinal screw 44 in the reduced upper end of the chuck-spindle.

The lower face of the friction disk 12 of 95 the hollow driving shaft 13 is recessed around its central bore which contains the reduced end of the spindle 29, to receive the shoulder of the thicker lower portion of said spindle, a space 45 being left between these 100 parts so that the shoulder will not come in frictional contact therewith.

All of the gears revolve while the chuck-spindle is coupled with either the upper driving gear 19 or the lower reversing 105 gear 28.

The reversing movement of the spindle to back the tap out of the work is effected by lifting the housing bodily upward a short distance, while the tool is in the work, until 110 the clutch-bar 36 clutches the upwardly projecting lugs 39 on the reversing gear 28, which is all the while revolving in a direction opposite to the driving gear 19 above. In most of the tapping tools of this kind, 115 the pulling out of the driving clutch is accompanied by much grinding and friction, which I have overcome by the devices now to be described. These devices consist of concaved seats 46 formed in opposite sides 120 of the arms of the clutch-bar 36 to receive the convex and tapering surfaces of the two clutch-pins 38 on the driving gear. These seats extend from the top of the clutch-bar downward a distance a little greater than 125 the length of the clutch-pins 38, as seen in Fig. 1, and have the general shape of the segment of a truncated cone. These seat formations result in allowing the bar to slide down and off the pins with greater smooth- 130

ness, reduced noise and shock, and thereby make the whole attachment much more comfortable to use, and also much more durable. The frictional surfaces might be slightly 5 changed in form and shape without departing from the scope of my invention.

The sides of the clutch-bar which engage with the locking lugs 39 on the top of the reversing gear are not recessed because the 10 frictional pressure on them is immaterial. It is desirable and necessary to prevent the reversing gear 28 from moving up with the spindle, and this I accomplish by forming a recessed hub 47 on the bottom of the reversing gear. This hub drops into a countersunk annular recess 49 in the top of base-plate 9. Horizontal retaining plates 48 enter the recess 49 in the hub and anchor it to the base-plate. These plates lie in trans- 15 verse recesses 50 so that their upper surfaces are flush with the top of the base-plate 9, in which position they are held by screws 51.

The chuck or tool holder on the lower end of the spindle 29 is secured thereto by a foot 25 66, clamping plate 72 and screws 73. As a further precaution against turning on the spindle, the bottom of the foot is provided with dowels 74 which enter corresponding holes in the chuck head 57. A "floating block" 53, having rectangular flat or squared sides, is located in a transverse recess 54 in the chuck head, and is adapted to have a free sliding movement across the axis of the spindle 29, being retained against sliding 30 out by a screw 55 and slot 56, (Figs. 5 and 6). Coöperating with the chuck head 57 is an axial guiding and centering recess 58 in the spindle, preferably conical in shape, and the upper end 59 of this recess, where the 35 latter comes to a point, is tapered to receive and center the butt end of the shank of a boring or tapping tool, such as shown in dotted lines in Fig. 5.

The floating block 53 is provided with a 40 vertical V-socket 60 arranged to be drawn by a set-screw 61 to a central position relative to the vertical axis of the centering recess 58, so that after the end 59 of said tap has first been introduced into the centering 45 recess 58, the tightening of the set-screw will bring the tap up into perfect alinement. This set-screw is threaded externally from end to end and operates in a removable plate 62 which covers the larger side of the 50 V-socket. An extension 63 on the outside of the plate provides a longer barrel for the set-screw to operate in and materially assists in keeping it from unscrewing. A polygonal flush socket 64 in the outer end of the 55 set screw is made to receive the squared end of an L-wrench by means of which the screw is worked. The removable plate 62 is secured to the floating block 53 by four screws 65. When the shank of a cutting tool is 60 passed up into the central recess of the chuck

its end will come in contact with the conical wall of the end thereof and be guided to the true center of the spindle. The tool however will not assume a true alinement throughout until the set screw 61 is tightened. The tightening or screwing up of the latter, when the tap is held tightly in the conical recess, draws the floating block and the vertical walls of the V-socket and shank of the tool up in true alinement and centers 70 the tool perfectly, in which adjustment it is shown in dotted lines in Fig. 5.

The means for locking the shafts 33 and 34 of the small intermediate gears of the reversing mechanism consists of a short 75 large-headed screw 67 which overlaps the ends of the spindles and fits in segmental recesses 68 therein as seen more clearly in Fig. 10.

The casing 1 is locked against rotation 80 while the tool is at work by a laterally extending arm 69 adapted to be removably screwed by hand into the side of the casing. A vertical stop arm (not shown) may be used in a vertical socket 70 to regulate the 85 depth of the tapping.

To hold the hollow shaft 13 rigid while the shank 7 is being screwed up or unscrewed, coinciding holes 71 are made through the casing 1, bushing 15, and hollow 90 shaft. The insertion of a pin through these 95 holes lock all three parts together.

Briefly described, the operation of my device is as follows: The shank 2 having first 100 been locked in the chuck 3 of the drill press and the mechanism set in motion, the whole attachment is lowered to the work on the table below by means of the hand lever 4 until the tap strikes the work, whereupon the attachment, excepting the spindle 29, will 105 continue to descend until the clutch-bar will have been raised sufficiently to clutch the driving gear 19, which has all the while been idly revolving, and the tap will be forced into the work. When the hole has been 110 tapped to the proper depth, the tap can be backed out by lifting up the lever 4 and raising the tool. The tap being still in the work will hold the spindle down until the clutch-bar 36 slips off the lugs 38, and onto the 115 lower lugs 39 of the reversing gear 28 which, rotating in the opposite direction, backs the tap out of the work. It will be seen that in the event of the excessive strain upon the tap, the upper friction clutch will be overcome and the driving cease. To release the 120 spindle from the reversing clutch the operator raises shaft 4 of the machine and reverses the machinery, sliding the clutch-bar 36 off the lower lugs.

It is evident that my device may be varied in many ways that might suggest themselves to those skilled in the art, without departing from the scope and spirit of my invention, and I wish it understood that I do not limit 125 130

myself to the exact construction herein shown but consider myself entitled to all such variations.

Having thus described my invention, what I claim as new and desire to secure by Letters Patent, is:

1. In a tapping attachment for drill presses, the combination with a casing containing driving and reversing gears and provided with means for holding it against rotation, of a chuck-spindle having a longitudinal recess, a pivotal retaining pin therein, a transverse clutch-bar loosely held by the pin in said spindle recess, retaining shoulders on said bar, and oppositely projecting pins upon the driving and reverse gears adapted to be alternately engaged by the bar.
2. In a tapping tool, a clutch-bar provided with transverse concaved tapering recesses in its opposite ends, in combination with a perforated chuck-spindle in which the bar is loosely held, and driving and reversing mechanism provided with convex tapering lugs adapted to fit and slide in and out of said recesses and to equalize the lateral strain on said bar in the coupling and uncoupling operations.
3. In a tapping tool, the combination with a spindle provided with a longitudinal bore in its upper end intersecting a transverse hole, a clutch bar loosely held in the transverse hole, a retaining screw at the upper end of said longitudinal hole, and a pin interposed between the screw and bar and loosely fitting in said bore, whereby the bar is allowed slight endwise play in said spindle, and whereby the pin has sidewise play to move with the bar.
4. A tapping tool or attachment provided

with a recessed casing inclosing a friction-driven spindle and adjustable friction devices, in combination with a friction regulating nut having holes in its periphery registering with the recess in the casing, whereby a temporary bar can be removably inserted and the friction devices thereby regulated from the outside of the casing.

5. In a tapping attachment, a housing having an offset provided with intermediate reversing gears, two parallel shafts set in the housing, and on which said gears are centered, said shafts being provided with external segmental recesses, and an intermediate locking screw having a circular head, the opposite sides of which intersect the circumferences of the shafts and fit into said recesses.

6. In a reversible tapping tool, the combination with a driven spindle, of a transverse loose clutch bar passing through the spindle, a longitudinal loose retaining pin in the spindle, and means for holding the pin in place.

7. In a tapping tool, the combination with a driven spindle, a shank therefor screwed in the top thereof, a bushing for the spindle, a housing or casing for the bushing, and registering transverse perforations in the spindle, bushing, and casing, whereby a locking pin can be inserted to hold said parts against turning while the shank is being screwed in or out of the spindle.

In testimony whereof, I affix my signature in presence of two witnesses.

JOHN H. DORMAN.
